COFFEE PERCOLATOR

Robert O. Ernest, Oak Park, Ill., assignor to Sunbeam Corporation, Chicago, Ill., a corporation of Illinois

Filed May 21, 1969, Ser. No. 17,251

Term of patent 14 years

Int. Cl. D7—04

U.S. Cl. D44—26

Fig.3.

Fig.4.

Fig.5.

FIG. 1 is a perspective view of a coffee percolator embodying my new design;

FIG. 2 is a side elevational view;

FIG. 3 is a front elevational view;

FIG. 4 is a rear elevational view; and

FIG. 5 is a top plan view thereof.

The characteristic feature of my design resides in the particular configuration of the base and cover combined with a percolator as shown.

I claim:

The ornamental design for a coffee percolator, as shown and described.
